CLAIM

The ornamental design for a case for portable electronic computing device, as shown and described.

DESCRIPTION

FIG. 1 is a front perspective view of a case for portable electronic computing device showing our new design.

FIG. 2 is a rear perspective view thereof.

FIG. 3 is a front elevational view thereof.

FIG. 4 is a rear elevational view thereof.

FIG. 5 is a left elevational view thereof.

FIG. 6 is a right elevational view thereof.

FIG. 7 is a top plan view thereof; and,

FIG. 8 is a bottom plan view thereof.

The broken lines in the drawing figures form no part of the claimed design and depict portions of the case for portable electronic computing device that form no part of the claimed design.
